UNITED STATES PATENT OFFICE.

FRANK F. FOWLE, OF CHICAGO, ILLINOIS.

INSULATOR.

1,219,450.

Specification of Letters Patent. Patented Mar. 20, 1917.

Application filed March 25, 1911. Serial No. 816,714.

To all whom it may concern:

Be it known that I, FRANK F. FOWLE, a citizen of the United States, residing at Chicago, in the county of Cook and State of Illinois, have invented new and useful Improvements in Insulators, of which the following is a full, clear, concise, and exact description, reference being had to the accompanying drawing, forming a part of 10 this specification.

My invention relates to insulators. One of the objects of my invention is to provide an efficient insulator of simple configuration which will effectively insulate an electric 15 conductor from its support. Another object is to provide an insulator which will have relatively high tensile strength and insulation resistance, and which can be manufactured economically.

20 In the accompanying drawings:

Figures 1 and 2 are partial sectional elevations of one form of insulator embodying my invention.

Fig. 3 is a half plan and half sectional 25 view thereof.

Fig. 4 is a perspective view of this form of insulator showing one method of suspension. Fig. 5 illustrates another method of suspension. Fig. 6 is a half elevation and 30 half section of another form of insulator embodying the invention.

The two forms of insulator illustrated are constructed preferably of porcelain or other suitable material and are adapted more particularly to be used with outdoor conductors suspended above ground upon poles, towers or other structures. The suspension of conductors in spans from insulating supports at intervals requires that the supports shall 35 have sufficient tensile strength to transmit the mechanical stresses between the conductor and the main supporting structure without failure, such as fractures, change of shape or cracking, and that they shall successfully resist the dielectric stresses without substantial leakage of current, loss of energy or without arcing, and furthermore that they shall be of such material and outline as to offer a very high electrical resistance to the arcing or leakage of current through or over the surface thereof. Furthermore these functions should obtain over a wide range of variations of temperature and precipitation and general atmospheric 55 disturbances.

The general form of insulator illustrated

in Figs. 1 to 5 inclusive comprises preferably two main elements; a hollow shell 1 that is somewhat hemispherical in shape and an interior bridge 2, extending from one side 60 of the shell to the other. Between the bridge and the apex of the shell there is provided a continuous opening or hole 3, leaving a free passage for a wire or cable. The shell 1 and the bridge 2 are traversed by a second 65 passage or hole 4 extending entirely through the insulator. Grooved entrances 5, 5, are provided to facilitate the insertion of a wire or cable through said passage 4, the bottom of which is made substantially straight to 70 prevent the formation of a pocket for water, which if confined therein and frozen might rupture the insulator.

Flaring entrances and grooves 6 are provided within the shell to facilitate the insertion of the wire or cable by which the conductor is suspended from the insulator.

One method of supporting the insulator and the conductor, is shown in Fig. 4. The wire or cable 7 passes through the hole 4 and supports the insulator directly while the wire or cable 8 passes through the hole 3 and is secured to the conductor 9 in any suitable manner. One satisfactory manner of attaching the wire 8 to the conductor 9 is 85 illustrated in this figure, and consists in wrapping the lower ends of said wire 8 about said conductor 9 in opposite directions, and then twisting together the ends of said wire to prevent unwrapping of the 90 same from the conductor. The supporting wire 7 may, of course, be secured in any suitable manner to a pole, cross-arm, tower or any other structure.

The form of insulator illustrated in Fig. 95 6 is characterized by the same general structural features as the first form described. When it is necessary to secure exceedingly high dielectric strength, the insulators may be hung in series or cascade arrangement as shown in Fig. 5. Of course either form of insulator or other modified forms thereof may be suspended in this manner. With the arrangement of interlinked loops illustrated, the conductor will be prevented from falling by the loops themselves if the body of the insulator should accidentally be broken.

The function of the bridge 2, is to resist the stresses between the two wire loops 110 mainly by its resistance to mechanical compressive stresses. It also forms one of the

dielectric media between these loops to resist puncture or break-down from electric stresses. Further, it forms one of the insulating media between the wire loops which minimizes the leakage or escape of current from the conductor to the supporting structure above.

The function of the shell is to protect the bridge and the supporting wire or cable 8 from precipitation of rain, hail, sleet or snow, and to exclude water or moisture as far as possible. A further function is to introduce a long leakage surface for arcing and current escape from one loop to the other, and to keep the interior part of this surface dry as far as possible. The insulator illustrated in Fig. 6 is provided with a very long leakage surface. In both of the forms which I have illustrated the precipitation of rain does not wet or moisten as large a portion of the whole surface between the conductor or the wire and the support which carries the insulator as is the case with other forms of insulators with which I am familiar.

I desire to have it understood that the invention is not limited to the embodiments described, as these forms were selected for the purpose of illustration only. I desire therefore to include all other suitable and equivalent forms which accomplish the desired results and fall within the scope of the appended claims.

What I claim as my invention and desire to secure by Letters Patent of the United States is:—

1. An insulator comprising a hollow inverted bowl having a bridging member spanning the interior thereof and integral with said bowl whereby a continuous pas-

sage is formed between said bridge and the closed end of said bowl, grooves on opposite sides of said bridge to facilitate the insertion of a cable through said passage, said insulator having a continuous opening there-through which traverses said bridge and terminates in upwardly flaring mouths to permit a supporting cable to be arranged therein with its supporting spans substantially vertical, the lower wall of said opening being arranged to drain moisture through said mouths at either side, said cables passing loosely through their respective passages in the form of loops thereby insuring flexibility of support, the lower edge of said bowl extending downwardly below said bridge member to shed moisture from the inner depending cable and insuring a long leakage path between said loops.

2. A device of the class described comprising a hollow inverted bowl, a central portion mounted within said bowl and joining the walls thereof at a plurality of points, thereby forming two continuous, oppositely directed passages for the reception of cables, one of said passages being entirely housed within said bowl and accessible only from beneath the same, the other of said passages terminating in outwardly flaring mouths on the exterior wall of said bowl, and grooves formed in the sides of said central portion and within said first-mentioned passage, substantially as shown and described.

In witness whereof, I have hereunto subscribed my name in the presence of two witnesses.

FRANK F. FOWLE.
